REV E, Dec. 2015.*Primary Examiner* — Selina Sikder(74) *Attorney, Agent, or Firm* — Crestron Electronics, Inc(57) **CLAIM**

The ornamental design for a wall mounted jack panel, as shown and described.

DESCRIPTION

FIG. 1 shows a front perspective view of a wall mounted jack panel.

FIG. 2 shows a front elevation view of the wall mounted jack panel.

FIG. 3 shows a left side view of the wall mounted jack panel.

FIG. 4 shows a right side view of the wall mounted jack panel.

FIG. 5 shows a top view of the wall mounted jack panel; and, FIG. 6 shows a bottom view of the wall mounted jack panel. The broken lines in the figures depict portions of the wall mounted jack panel that form no part of the claimed design.
